tion Sept. 29, 1961, Ser. No. 66,959

Term of patent 14 years

(Cl. D24—1)

FIG.1.

FIG.2.

FIG. 3

FIG. 4

FIG. 1 is a front perspective view illustrating our new design for a treadle control for dental apparatus;

FIG. 2 is a rear perspective view of the control of FIG. 1;

FIG. 3 is a perspective view similar to FIG. 1, showing a modified form of the new design for a treadle control for dental apparatus; and

FIG. 4 is a rear perspective view, similar to FIG. 2, and showing the rear portions of FIG. 3.

The essential features of our design reside in the portions shown in full lines.

This application is a continuation of our copending applications, Serial Nos. D. 57,245 and D. 57,246 filed August 21, 1959, and now abandoned.

We claim:

The ornamental design for a treadle control for dental apparatus, as shown and described.
